APPARATUS FOR FILLING RECEPTACLES

Richard D. Anderson, Baton Rouge, La., assignor
to Standard Oil Development Company, a cor-
poration of Delaware

Application January 26, 1933, Serial No. 653,578

11 Claims. (Cl. 226—96)

This invention relates to improvements in apparatus for filling receptacles with fluid. More particularly it relates to an improved apparatus for filling cans with grease.

5 It is an object of this invention to provide a rotary apparatus for successively measuring predetermined quantities of grease and for successively ejecting the measured grease into suitable receptacles.

10 It is a further object to provide a construction whereby the measuring cylinders are filled at one location and are discharged at a separate location. Still another object is to control the operation of filling the measuring cylinders 15 with grease and the ejection of the grease from the cylinders while the cylinders are in motion.

15 Other objects will be apparent from the specification and from the accompanying drawings in which latter—

20 Fig. 1 is a front elevational view with parts broken away of the device;

Fig. 2 is a rear elevational view of the device with parts broken away;

25 Fig. 3 is a top plan view of the device with parts broken away taken on line III—III of Fig. 5;

Fig. 4 is a transverse sectional view of the device taken along the line IV—IV of Fig. 3;

30 Fig. 5 is a transverse sectional view of the device taken along the line V—V of Fig. 3;

Fig. 6 is a cross sectional view of the device taken along the line VI—VI of Fig. 1 looking up;

35 Fig. 7 is a cross sectional view of the device taken along the line VII—VII of Fig. 2;

Fig. 8 is a detail of the valve seat showing orifices;

40 Fig. 9 is a detail or side view of valve head and stem;

Fig. 10 is a top view of valve head and section through stem showing spaced openings;

Fig. 11 is an assembly view showing valve head and stem over valve seat when valve is closed;

45 Fig. 12 is a top detail view of piston rod and cam rolls; and

Fig. 13 is a side detail view of piston rod and cam rolls.

50 Referring particularly to the drawings, reference numeral 1 designates the bed plate or supporting truck of the device. A tubular supporting column 2 extends upwardly from the bed plate 1. The supporting column is divided by a bottom plate 3 and a top plate 4 to form a reservoir 5 for the fluid such as grease. The grease is supplied to the reservoir 5 through a conduit 6 by means of a suitable pump 7, under a suitable pressure such as approximately 4 pounds per square inch. A cylinder 8 communicates with the upper portion of the reservoir

through a conduit 9. A piston 10 reciprocably mounted within the cylinder is guided by suitable guide rods 11 which are received in openings in the piston head 12. The reservoir 5 is provided with a laterally elongated exhaust port 15 for delivery of grease from the reservoir. The piston 10 is weighted sufficiently to maintain a uniform flow of grease through the exhaust port 15 even though there should be a variation in the pump pressure upon the grease 10 entering the reservoir 5 which might cause uneven flow of grease into the reservoir.

The lubricant is delivered from the reservoir 5 to a measuring and distributing apparatus which is rotatably mounted with respect to the tubular support column 2. The measuring apparatus comprises a tubular bracket 20 which is rotatably supported upon an annular flange 21 which projects outwardly from the support column 2. The tubular bracket 20 is provided at its opposite ends with gland nuts 22, the lower one of which revolves upon a thrust roller bearing 23. A stuffing box 24 is provided at top and bottom of the bracket 20. The bracket 20 is driven in rotation in a clockwise direction as viewed in Fig. 3 in a manner to be later described. A plurality of measuring cylinders *a* to *p* inclusive are supported radially exteriorly of the bracket 20. Empty cans *X* which are to be filled with grease are fed from a table 25 manually or otherwise to a revolving table 26 between spacing fingers 26a.

The measuring cylinders are positioned in a circle just above the pockets formed by the spacing pins 26a. The measuring cylinders each include a cylindrical body 27 which is connected adjacent its base to the bracket 20 by means of a tubular arm 28. The interior of each tubular arm 28 communicates with one of a plurality of openings 29 on the bracket 20. The cylinder 27 is provided at its bottom with a hopper 31 having a discharge opening 32. A valve 33 extends across the cylinder above the hopper. The valve seat 33' is provided with a plurality, such as seven, of spaced orifices 34. A valve disposed within the cylinder has a valve head 35 extending across the cylinder, and a valve stem 37 projecting upwardly from the valve head. The valve head is provided with a plurality such as seven openings 38. The valve is adapted to be rotated so as to successively align and disalign the openings 38 with the orifices 34, see Figs. 8, 9, 10 and 11. The capacity of the cylinder is varied by means of an adjustable cover 45.

The grease is ejected from the measuring cylinder by means of a piston 46 having a tubular piston rod 47. The piston 46 is reciprocable downwardly in the cylinder as far as ring 48 which is fixed in position within the cylinder at

the opening of the passageway 29 with the interior of the cylinder. The ring 48 is perforated to permit passage of grease into the cylinder. The ring 48 prevents the valve 36 from rising in the cylinder and prevents the piston 46 from dropping below the port opening. The valve stem 37 extends non-rotatably through the piston head 46 into the tubular piston rod 47 whereby the piston can be reciprocated longitudinally of the valve stem and rotation of the piston causes rotation of the valve stem. The piston rod carries at its upper end a vertically facing roll 49 which is adapted to engage a cam 50 for forcing the piston downwardly in the cylinder to eject grease from the cylinder into a receptacle. The cam 50 is positioned to be engaged by the roll 49 from the position of the measuring cylinder *b* as shown in Fig. 3, to the position of the measuring cylinder *i* as shown in Fig. 3. The cam 50 is inclined downwardly from a position opposite the measuring cylinder *b* to a position opposite the measuring cylinder *i*. As the measuring cylinders are rotated in a clockwise direction, as viewed in Fig. 3, the piston 46 is gradually forced downwardly to eject the grease from the cylinders into the cans *X*.

The valve 36 for opening and closing the bottom of the measuring cylinder is actuated by the following arrangement of parts: The piston rod is provided with laterally extending brackets 57 and 58, see Figs. 12 and 13, which carry laterally facing cam rolls 59 and 60 respectively. The rolls 59 and 60 follow the side walls 61 and 62 respectively of an annular camway 63 formed in the cover plate 4. The walls 61 and 62 of the camway are inclined radially inwardly at 64 and 65 respectively and are inclined radially outwardly at 66 and 67 respectively, as clearly shown in Figs. 3 and 6. As the assembly of measuring cylinders rotates in a clockwise direction, as viewed in Fig. 3, the roll 59 in passing from the position of measuring cylinder *a* to that of measuring cylinder *b* engages the inclined surface 64 of the camway retarding the movement of the roll 59 sufficiently to cause the piston rod 47 to be rotated about its longitudinal axis thereby turning the valve 36 to bring the ports 38 and 34 into alignment to permit discharge of grease from the measuring cylinder. The discharge openings are maintained in alignment from the position of the measuring cylinder *b* to the position of the measuring cylinder *i*, during which period the grease ejecting piston 46 is descending within the cylinder.

Upon leaving the position of the measuring cylinder *i* the roll 60 is caused to ride up the radially outwardly inclined wall 67 of the camway thereby retarding the peripheral movement of the cam roll 60 and causing the piston rod 47 to be rotated about its longitudinal axis, thereby turning the valve 36 sufficiently to bring the ports 38 and 34 at the bottom of the measuring cylinder out of alignment. The valve 36 is closed in the bottom of the measuring cylinder and the cylinder is ready to receive a new charge of grease. The cans *X* are thus filled with grease in predetermined amounts such as one pound. Upon continued rotation of the table 26, the filled cans are engaged by a tapered arm 75 which diverts the cans away from the revolving table 26.

Upon continued rotation of the measuring cylinder assembly the inlet port 29 to each measuring cylinder is brought into alignment with

the oblong port 15 in the wall of reservoir 5. Pressure is maintained in the reservoir 5 by a grease pump and the weighted piston. The valve 36 being in closed position, the grease is injected into the measuring cylinder under sufficient pressure to elevate the piston 46 to its uppermost position thus filling the measuring cylinder with a predetermined amount of grease. Further rotation of the assembly in a clockwise direction, as viewed in Fig. 3, brings the 10 filled measuring cylinder to the position indicated at *a* where a fresh can is positioned beneath the measuring cylinder.

The assembly is driven in rotation by means of a motor 80 which actuates a worm shaft gear 81; see Figs. 1 and 2. A worm, not shown, driven by the worm gear 81 drives a worm gear 82. The worm gear 82 drives a shaft 83 and an operating pinion 84 which meshes with a gear 85 affixed to the rotatable table 26.

By the construction described, the measuring cylinders 27 are filled at one place and are discharged at another. A plurality such as seven measuring cylinders are permitted to discharge grease at the same time, and the grease in the cans is allowed to level and not pile up. The valve 36 is opened and closed and the piston 46 is pressed down while the cylinders 27 are in motion. The valve 36 can be operated when the piston 46 is in either its upper or lower position, since the valve stem 37 reciprocates in the hollow piston rod 47.

Various changes may be made within the scope of the appended claims in which it is desired to claim all novelty inherent in the invention as broadly as the prior art permits.

I claim:

1. Apparatus for filling receptacles, comprising a tubular bracket mounted for rotation, a table for spaced receptacles extending around and carried by the bracket, a plurality of measuring cylinders extending around and carried by the bracket over and opening toward the receptacles, means for rotating the bracket, means including a pump and piston for successively injecting fluid into each cylinder, and means for successively ejecting the fluid from the cylinders into the receptacles.

2. Apparatus for filling receptacles, comprising a cylindrical reservoir, means for injecting fluid into the reservoir, a weighted piston communicating with the reservoir for maintaining the fluid under pressure, a tubular bracket mounted for rotation, a table for spaced receptacles extending around and carried by the bracket, a plurality of measuring cylinders extending around and carried by the bracket over the receptacle to be filled, means for rotating the bracket, the bracket having means for successively passing the fluid from the reservoir into the cylinders, and means for successively ejecting the fluid from the cylinders into the receptacles.

3. Apparatus for filling receptacles comprising a bracket mounted for rotation, a table for spaced receptacles extending around and carried by the bracket, a plurality of measuring cylinders extending around the bracket, a discharge outlet for each measuring cylinder, a piston in each measuring cylinder reciprocable toward and from the discharge outlet and having a tubular piston rod, means for reciprocating the piston, a valve seat in the cylinder having spaced openings, a valve in the cylinder, the stem of the valve being reciprocable non-rotatably

through the piston into the tubular piston rod, means for rotating the piston and valve to open the valve, and means for forcing the piston toward the opening whereby a measured quantity of fluid is ejected from the cylinder into the receptacle.

4. Apparatus for filling receptacles, comprising a bracket mounted for rotation, a table for spaced receptacles extending around and carried by the bracket, a plurality of measuring cylinders extending around and carried by the bracket, the cylinders having discharge openings over the receptacles, a piston in each measuring cylinder reciprocable toward and from the discharge outlet and having a tubular piston rod, a stationary semi-circular cam disposed opposite the pistons and inclined toward the pistons whereby the pistons are successively forced toward the discharge outlet, a valve controlling the outlet and associated with the piston, and means for rotating the piston and valve to control the outlet.

5. Apparatus for filling receptacles, comprising a cylindrical reservoir for fluid under pump pressure and containing a discharge orifice in its side wall, a tubular bracket mounted for rotation around the reservoir, a table for spaced receptacles extending around and carried by the bracket, a plurality of measuring cylinders extending around and carried by the bracket, the measuring cylinders having discharge openings over the receptacles, means for rotating the bracket, the bracket having passageways leading from the cylinders through the bracket on a level with the discharge orifice in the side wall of the reservoir whereby the cylinders are successively filled with fluid at a given position of their rotary travel, a valve controlling the discharge outlet in each cylinder, a piston in each measuring cylinder reciprocable toward and from the discharge outlet, means for successively actuating the valves, and pistons and spacing means at the passageways to prevent the pistons from closing the passageways.

6. Apparatus for filling receptacles, comprising a bracket mounted for rotation, a table for spaced receptacles extending around and carried by the bracket, a plurality of measuring cylinders extending around and carried by the bracket and opening over the receptacles, a source of fluid under pressure communicating with the cylinders, a rotary valve for the discharge opening of each cylinder, a piston reciprocable and rotatable in each cylinder and operatively connected to its valve, means for rotating each piston to successively close and open its valve, and means for actuating the piston to eject fluid through the open valve.

7. Apparatus for filling receptacles, comprising a bracket mounted for rotation, a table for spaced receptacles extending around and carried by the bracket, a plurality of measuring cylinders extending around and carried by the bracket and each having a discharge opening over the receptacles, means including a pump and piston for successively injecting fluid into each cylinder, a rotary valve for the discharge opening of each cylinder, a piston reciprocable and rotatable in each cylinder and operatively connected to its valve, means for rotating each piston to successively close and open its valve, and means for actuating the piston to eject fluid through the open valve.

8. Apparatus for filling receptacles, comprising a bracket mounted for rotation, a table for spaced receptacles extending around and carried by the bracket, a plurality of measuring cylinders extending around and carried by the bracket and opening over the receptacles, a source of fluid under pressure communicating with the cylinders through an inlet, each cylinder having an outlet, a rotary valve between the inlet and outlet of each cylinder and having a valve stem, a piston reciprocable and rotatable in each cylinder and operatively connected to its valve stem, means for rotating each piston to successively close and open the valve, and means for actuating each piston to eject fluid through the open valve.

9. Apparatus for filling receptacles, comprising a bracket mounted for rotation, a table for spaced receptacles extending around and carried by the bracket, a plurality of measuring cylinders extending around and carried by the bracket and opening over the receptacles, each measuring cylinder having an inlet and an outlet, a rotary valve between the inlet and outlet and having a valve stem, a piston reciprocable and rotatable in each cylinder and operatively connected to the stem of its valve, cam followers associated with each piston, a circular camway disposed in the path of the cam followers operable to turn the pistons to open and close the valves, a second circular camway disposed in the path of the piston rods operable to control longitudinal reciprocation of the pistons, whereby the fluid is ejected through the open valves of the cylinders.

10. In apparatus for filling a receptacle, a measuring cylinder having an inlet and an outlet, a valve seat extending across the cylinder between the inlet and outlet and having at least one opening, a rotary valve the head of which has at least one opening adapted to be rotated into alignment with the opening of the valve seat and which extends across the cylinder, an annular sleeve fixed within the cylinder operative to hold the valve head against the seat, and a piston reciprocable and rotatable in the cylinder and operatively connected to the valve whereby the piston can be rotated to successively close and open the valve and can be reciprocated to eject fluid through the open valve.

11. In apparatus for filling a receptacle, a measuring cylinder having an inlet in its side wall and a bottom outlet, a valve seat extending across the cylinder between the inlet and outlet and having at least one opening, a rotary valve the head of which extends across the cylinder and has at least one opening adapted to be rotated into alignment with the opening of the valve seat, and a piston reciprocable and rotatable in the cylinder and operatively connected to the valve, an annular sleeve fixed within the cylinder across the inlet operative to hold the valve head against the seat and having an opening communicating with the inlet, the sleeve preventing movement of the piston to close the inlet, rotation of the piston being adapted to successively close and open the valve, and the reciprocation of the piston being adapted to eject fluid through the open valve.

RICHARD D. ANDERSON.
